DESIGN FOR A PLATE OR THE LIKE

Mary Sebold, New York, N. Y., assignor to Mayer
China Company, Beaver Falls, Pa., a corporation of Pennsylvania

Application January 11, 1947, Serial No. 136,100

Term of patent 14 years

(Cl. D44—15)

To all whom it may concern:

Be it known that I, Mary Sebold, a citizen of the United States, residing at New York, in the county of New York and State of New York, have invented a new, original, and ornamental Design for a Plate or the like, of which the following is a specification, reference being had to the accompanying drawing, forming part thereof.

In the drawing:

The figure is a plan view of a plate, showing my new design. The ornamentation shown is continued about the circumference of the plate.

I claim:

The ornamental design for a plate or the like, as shown and described.

MARY SEBOLD.
